DISH

Julius Epstein, West Hempstead, N. Y.

Application July 18, 1947, Serial No. 140,368

Term of patent 3½ years

(Cl. D44—10)

To all whom it may concern:

Be it known that I, Julius Epstein, a citizen of the United States, residing in the city of West Hempstead, county of Nassau, and State of New York, have invented a new, original, and ornamental Design for a Dish, of which the following is a specification, reference being had to the accompanying drawing, forming part thereof.

On the drawings,

Fig. 1 is a top plan view of a dish, showing my new design;

Fig. 2 is a partial vertical sectional view, substantially on the line 2—2, of the dish shown in Fig. 1; and

Fig. 3 is a bottom plan view thereof.

The dish includes a concave glass portion shown in section in Fig. 2, through which is visible a design on the inside face of the bottom of the outer section of the dish.

The dominant features of the design reside in the parts shown in full lines.

I claim:

The ornamental design for a dish, substantially as shown and described.

JULIUS EPSTEIN.
